UNITED STATES PATENT OFFICE.

LUTHER L. DAVIS, OF KINGSVILLE, TEXAS, ASSIGNOR OF ONE-HALF TO GEO. L. SPIVEY,
OF CORPUS CHRISTI, TEXAS.

JOURNAL-BOX.

1,297,111.

Specification of Letters Patent. Patented Mar. 11, 1919.

Application filed April 2, 1918. Serial No. 226,209.

To all whom it may concern:

Be it known that I, LUTHER L. DAVIS, a citizen of the United States, residing at Kingsville, in the county of Kleberg, State of Texas, have invented certain new and useful Improvements in Journal-Boxes; and I do hereby declare the following to be a full, clear, and exact description of the invention, such as will enable others skilled in the art 10 to which it appertains to make and use the same.

The invention relates to a journal box, and more particularly to the class of railway freight car journal boxes.

The primary object of the invention is the provision of a journal box of this character, wherein one side wall of the box has a removable section so that the journal or the axle can be taken from the box while the truck is under the car, and also the bearings can be conveniently removed when the occasion requires.

Another object of the invention is the provision of a journal box of this character wherein the key for the journal bearing and the latter are held in place to avoid relative displacement with respect to each other and also with respect to the box, the dust guard being mounted in the box in a novel manner and the possibility of leakage of oil from said box is eliminated, while the removal and renewal of the bearings is facilitated.

A further object of the invention is the provision of a journal box of this character, wherein the journal axle is economically and efficiently lubricated.

A still further object of the invention is the provision of a journal box of this character, which is simple in construction, possessing maximum strength and durability, assuring easy access thereto and enabling the convenient placing of the journal axle therein or its removal therefrom, and also which is inexpensive to manufacture.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such

changes and modifications come within the scope of the appended claims.

In the accompanying drawings:

Figure 1 is a side elevation of a journal box constructed in accordance with the invention with the arched bars and the locking key engaged therein.

Fig. 2 is a vertical longitudinal sectional view.

Fig. 3 is a vertical transverse sectional view taken on the line 3—3 of Fig. 1.

Fig. 4 is a fragmentary horizontal sectional view.

Fig. 5 is a plan view of the journal bearing key.

Fig. 6 is a perspective view of the removable section of the box looking toward its inner face.

Fig. 7 is an inner end elevation of the journal box with the journal therein the latter being a transverse section.

Fig. 8 is an end elevation of the journal bearing and the key therefor when fitted together.

Similar reference characters indicate corresponding parts throughout the several views in the drawings.

Referring to the drawings in detail, A designates generally the journal box which as usual has an opening at its outer end normally closed by the journal box cover 10, the same being pivotally hung in the ordinary well known manner from the top of the box and on the opening thereof access may be had to the interior of the box for the introduction of oil and waste when the occasion requires. The box A is fast between the arched bars 11 which have their ends above and below said box extended beyond one side thereof for a purpose presently described.

Formed in one side of the box A longitudinally thereof is a substantially rectangular shaped opening in which is removably fitted a door or section 12, the opening being extended through the inner end of the box A and the upper longer edge and the outer closed end edge of this opening is inwardly beveled as at 13 while the lower longer edge of said opening is formed with a rabbet 14 and the door or section 12 at the edges companions to the edges 13 and 14 are correspondingly shaped thereto to have the door tightly fit the opening to avoid the leakage

of oil from the box A about the joint between said door and box.

The inner end of the journal box A is formed with the opening 15 for the axle journal 16, the inner end of said box at one side of the opening 15 being cut away at 17 to form a continuation of the side opening in said box so that the journal 16 can be passed through the side opening into the box or removed therethrough from the same.

The door or section 12 at the inner end thereof has formed thereon a right angular extension 18 which occupies the cutaway portion 17 in the inner end of the box A 15 when the door or section 12 is mounted in the side opening of the latter. Removably fitted in the projected ends of the arched bars 11 is a wedging key 19 which lies across the outer face of the door or section 12 when in the side opening in the box A 20 to hold fast the said door or section 12 in place, the door or section on its outer face being formed with spaced abutments 20 to engage with opposite sides of the key 19, 25 which is held locked or secured by a cotter pin 21 mounted in the lower end of said key to prevent the working loose of the same, yet permitting the removal of the key when the occasion requires.

Mounted interiorly of the box A at the inner end thereof is a dust guard 22 of the usual construction and is held for vertical sliding movement by the internal dust collar 23 which is formed on the box and the door or section respectively. The dust guard 22 is removable from one side of the box A which is formed with notches 24 in the side thereof above and below the side opening for permitting the removal of the dust 30 guard. The door or section 12 is formed with the wings 25 which fit in and close the notches 24 when said door or section is engaged in the side opening in the box.

Removably held within the box A above the axle journal 16 is the bearing of brass 26 which is formed with the end shoulders 27 to engage the ends of a seat 28 for the bearing on a wedge or key 29 which is removably fitted within the box A superimposed upon the bearing 26 and plays against the front end of said box and the collar 23 to avoid longitudinal displacement thereof, the bearing being formed with the usual side lugs 30 to engage complementary side lugs 31 formed 35 interiorly of the box on the side walls thereof and the door or section 12. It will be noted that the bearing 26 and the key 29 will be held against relative movement with respect to each other.

The box A is adapted to receive lubricant and waste as usual, the lubricant being absorbed by the waste which supplies the same to the journal 16 for the thorough lubrication thereof.

On the removal of the door or section 12

from the side opening in the box A the journal 16, dust guard 22, bearing 26 and the key 29 therefor can be readily removed from said box while the truck is beneath the car.

From the foregoing it is thought that the 70 construction and manner of use of the invention will be clearly understood and therefore a more extended explanation has been omitted.

What is claimed is:—

1. In a journal box of the character described, a removable door section at one side of the box for permitting the introduction and removal of the journal into and from the box, and means for securing the door 80 section in place.

2. In a journal box of the character described, a dust guard fitted in the box at its inner end and removable through one side of said box, said box having an opening in 85 one side thereof for permitting the introduction and removal of a journal into and from the box, and a removable section closing said opening and retaining the dust guard in the box.

3. In a journal box of the character described, a dust guard fitted in the box at its inner end and removable through one side of said box, said box having an opening in 95 one side thereof for permitting the introduction and removal of a journal into and from the box, a removable section closing said opening and retaining the dust guard in the box, and a detachable wedging key disposed across the section to hold the same 100 secure in the opening in the side of the box.

4. In a journal box of the character described, a journal brass key fitted therein against longitudinal displacement within the box and having a seat, a journal brass 105 adapted to be superposed upon a journal axle when mounted in the box and having end abutments to engage the ends of the seat in the key when the brass is in the seat to prevent relative displacement of the key and 110 brass, ribs formed on opposite side walls interiorly of the box, and lugs on the brass and engageable with the ribs.

5. In a journal box of the character described, a journal brass key fitted therein 115 against longitudinal displacement within the box and having a seat, a journal brass having end abutments to engage the ends of the seat in the key when the brass is in the seat to prevent relative displacement of the key 120 and brass, ribs formed on opposite side walls interiorly of the box, lugs on the brass and engageable with the ribs, said box being formed with a side opening for the introduction and removal of a journal into and 125 from the box, and a door section removably secured in the opening.

6. In a journal box of the character described, a journal brass key 130 fitted therein against longitudinal displacement within 135

the box and having a seat, a journal brass having end abutments to engage the ends of the seat in the key when the brass is in the seat to prevent relative displacement of
5 the key and brass, ribs formed on opposite side walls interiorly of the box, lugs on the brass and engageable with the ribs, said box being formed with a side opening for the introduction and removal of a journal into
10 and from the box, a door section removably

secured in the opening, and a dust guard arranged within the box at its rear end and removable through the side opening.

In testimony whereof, I affix my signature, in the presence of two witnesses.

LUTHER L. DAVIS.
